UNITED STATES PATENT OFFICE.

MARCUS JOHNSON, OF BROOKLYN, NEW YORK.

PLEASURE-RAILWAY.

1,351,658.

Specification of Letters Patent. Patented Aug. 31, 1920.

Application filed November 4, 1919. Serial No. 335,571.

To all whom it may concern:

Be it known that I, MARCUS JOHNSON, a citizen of the United States, and a resident of the city of New York, borough of Brooklyn, in the county of Kings and State of New York, have invented a new and Improved Pleasure-Railway, of which the following is a full, clear, and exact description.

10 The object of the invention is to provide a new and improved pleasure railway for use in pleasure resorts, parks, exhibition grounds, fairs and other places of amusement, and arranged to accommodate a large 15 number of persons at a time and to provide an exhilarating ride for the participants.

Another object is to provide a pleasure railway which is simple and durable in construction and safe in operation.

20 With these and other objects in view, the invention consists of certain novel features of construction as hereinafter shown and described and then specifically pointed out in the claims.

25 A practical embodiment of the invention is represented in the accompanying drawings, forming a part of this specification, in which similar characters of reference indicate corresponding parts in all the views.

30 Figure 1 is a plan view of the pleasure railway;

Fig. 2 is an enlarged sectional side elevation of a portion of the pleasure railway and showing more particularly one of the cars, 35 the platform on which the cars travel, and the propelling means for the cars;

Fig. 3 is an enlarged cross section of the pleasure railway on the line 3—3 of Fig. 1;

Fig. 4 is a sectional plan view of the 40 same on the line 4—4 of Fig. 3; and

Fig. 5 is an enlarged cross section of one of the guide pins for the cable and mounted in the guideway.

On a suitably constructed platform 10 is 45 formed an endless slot having segmental end portions 11 and 12 and connecting side portions 13 and 14 of undulating and zigzag shape and connecting tangentially with the segmental end portions 11 and 12, as will be 50 readily understood by reference to Fig. 1. On the top of the platform 10 are adapted to travel a number of cars 15 each having a car base 16 and a car body 17, preferably made circular, and provided with a centrally

arranged king pin 18 engaging a bearing 55 19 formed on the car base 16 to allow the car body 17 to turn on the car base 16 and be carried bodily along by the car base 16 when the latter is propelled over the platform, as hereinafter more fully explained. 60 The car body 17 is preferably made circular and provided with a circularly arranged to seat 20 to accommodate a number of persons at a time. The under side of the car base 16 is provided with rollers 21 65 mounted to travel on the platform 10, sundry of the rollers 21 being on one side of the slot and sundry on the other side thereof.

The forward end of each base 16 is provided with a projection 25 having a bearing 70 26 engaged by the upper end of a vertically extending pivot pin 27 extending downward through the platform slot, and the lower portion of this pivot pin 27 is provided with two collars 28 and 29 mounted to travel in 75 a guideway 30 arranged beneath the platform 10 and following the platform slot formed of the end portions 11 and 12 and the side portions 13 and 14, as above explained. The guideway 30 is preferably 80 formed of angle irons 31 and 32 located on opposite sides of the platform slot (see Fig. 3). The outer angle iron 31 is continuous and follows the outer wall of the platform slot while the inner angle iron 32 follows 85 the inner wall of the side portions 13 and 14 and the end portion 12 of the platform slot, and the ends of this inner angle iron 32 terminate at the segmental end slot portion 11. 90

The portion 33 of each pivot pin 27 intermediate the collars 28 and 29 is enlarged and engaged by a tubular split conical wedge 35 clampingly engaging a corresponding portion of an endless traveling cable 40 and for 95 imparting a traveling motion to the cars 15 over the platform 10 with the cars approximately in the path indicated by the platform slot. In order to impart a traveling motion to the cable 40 use is made of a drum 41 in the 100 form of a channel beam, to which lead tangentially the ends of the inner angle iron 32, and on the peripheral face of this drum 41 are secured spaced lugs 42 adapted to engage each pivot pin 27 to positively move the 105 same along and thus impart a traveling motion to the cable 40. The drum 41 is secured to a rim 50 (see Figs. 3 and 4) mount-

ed at its inner edge on rollers 51 journaled on the circular support 52. On the under side of the rim 50 is secured a bevel gear wheel 55 in mesh with a pinion 56 (see Fig. 1) secured on a shaft 57 driven by a suitable motor 58 installed below the platform 10. It will be noticed that when the motor 58 is running a rotary motion is given to the bevel gear wheel 55, the rim 50 and the drum 41 whereby the lugs 42 of the drum impart a continuous traveling motion to the cable 40. The pivot pins 27 on account of being fixed to the traveling cable 40 are carried along by the latter and consequently the cars 15 are bodily pulled over the platform 10. As the pivot pins follow the guideway 30 it is evident that the cars are pulled along over the path approximately conforming to the shape of the platform slot formed of the segmental end portions 11 and 12 and the zig-zag side portions 13 and 14 but the cars are free to swing more or less sidewise so as to extend more or less to one side or the other of the corresponding slot portions 13 and 14, as will be readily understood by reference to Fig. 1. During the travel of the cars along the segmental end slot portions 11 and 12 the cars are held in central position relative to the slot portions and during the time the cars travel along these portions a rotary motion is given to the car bodies 17 to rotate the latter on their car bases 16. For the purpose mentioned each car body 17 is provided exteriorly near its bottom with a gear wheel 60 moving in mesh with a segmental gear wheel 61 concentric with the end slot portion 11 and located outside of the same, as plainly shown in Fig. 1. Thus when a car moves to this end section its gear wheel 60 moves in mesh with the fixed segmental gear wheel 61 and as the car is caused to travel along bodily its body 17 is rotated on the car base 16. At the other end of the pleasure railway is arranged a segmental gear wheel 62 concentric with the end slot portion 12 but located inside thereof and hence when a car approaches this end of the pleasure railway the gear wheel 60 moves in mesh with the fixed gear wheel 62, and, as the car is propelled along, its car body 17 is rotated but in a reverse direction from that it had at the other end of the pleasure railway. A segmental guard rail 63 is arranged on the platform 10 concentric with the end slot portion 12 and outside of the same to hold the car body in a central position during its travel around this end of the pleasure railway. A similar circular guard rail 64 is mounted on the platform 10.

In order to prevent undue binding of the cable 40 during its travel along the zigzag portions 13 and 14, use is made of guide pins 80, similar to the pivot pins 27, and provided with collars 81 and 82 traveling in the guideway 30 formed by the angle irons 31

and 32. Each guide pin 80 is provided with a split clamping sleeve 83 clampingly engaging the cable 40 and each guide pin 80 is preferably located immediately in the rear of a car, as plainly shown in Fig. 1. 70

It will be noticed that by the arrangement described the cars 15 are propelled over the platform 10 along a course which is partly zigzag and partly segmental, and at the same time the cars are free to swing 75 sidewise owing to the pivotal connection of the car bases 16 with the propelling pins 27 attached to the cable 40.

It will further be noticed that the car bodies 17 are caused to rotate in opposite directions during the time they travel over the segmental end portions of the pleasure railway. 80

From the foregoing it will be seen that a very exhilarating ride is provided for the occupants of the car bodies 17. 85

It will further be noticed that a large number of cars are caused to travel simultaneously over the platform 10 and hence a large number of persons can be accommodated at a time. 90

Having thus described my invention, I claim as new and desire to secure by Letters Patent:

1. A pleasure railway, comprising a platform provided with an endless guideway, a plurality of cars mounted to travel on the said platform and extending across the said guideway, and propelling means arranged underneath the platform and having connecting means extending through the said guideway and each connected with a corresponding car to move the latter forward and to allow it to swing sidewise on the platform while traveling thereon. 95

2. A pleasure railway, comprising a platform provided with an endless guideway, a plurality of cars mounted to travel on the said platform and extending across the said guideway, and propelling means arranged underneath the platform and having connecting pivot pins extending up through the said guideway and on which the cars are mounted to swing sidewise while traveling on the platform. 110

3. A pleasure railway, comprising a platform having an endless guideway, cars each having a base and a car body mounted to turn on the said base, the latter being mounted to travel on the said platform, and propelling means having connecting devices following the said guideway and on which the said car bases are mounted to swing. 120

4. A pleasure railway, comprising a platform having an endless guideway, cars each having a base and a car body mounted to turn on the said base, the latter being mounted to travel on the said platform, and propelling means arranged below the platform and provided with pivot pins extending up- 130

ward through the guideway and on which the said car bases are pivoted to allow the cars to swing sidewise.

5. A pleasure railway, comprising a platform having an endless guideway, cars each having a base and a car body mounted to turn on the said base, the latter being mounted to travel on the said platform, propelling means in the form of an endless traveling cable arranged below the said platform, a driving drum around which passes the said cable, means connecting the said drum with the cable to impart a traveling motion, and pivot pins extending upward from the cable 10 through the said guideway, the said car bases being mounted to swing on the said pivot pins.

6. A pleasure railway, comprising a platform having an endless guideway, cars each 20 having a base and a car body mounted to turn on the said base, the latter being mounted to travel on the said platform, propelling means in the form of an endless cable arranged below the said platform, a driving drum provided on its peripheral face 25 with spaced lugs, and pivot pins attached to the said cable and projecting through the said guideway, the forward ends of the car bases being pivoted on the said pivot pins 30 to pull the cars along and to allow the cars to swing sidewise, the said pivot pins being adapted to be engaged by the said drum lugs to impart a traveling motion to the said cable.

35 7. A pleasure railway, comprising a platform having an endless guideway, cars each having a base and a car body mounted to turn on the said base, the latter being mounted to travel on the said platform, propelling 40 means having connecting devices following the said guideway and on which the said car bases are mounted to swing, and means for rotating the said car bodies.

8. A pleasure railway, comprising a platform having an endless guideway, cars each 45 having a base and a car body mounted to turn on the said base, the latter being mounted to travel on the said platform, propelling means having connecting devices following 50 the said guideway and on which the said car bases are mounted to swing, and means at the ends of the said guideway for rotating the said car bodies.

9. A pleasure railway, comprising a platform having an endless guideway, cars each 55 having a base and a car body mounted to turn on the said base, the latter being mounted to travel on the said platform, propelling means in the form of an endless cable arranged below the said platform, a driving drum provided on its peripheral face with spaced lugs, pivot pins attached to the said cable and projecting through the said guideway, the forward ends of the said car bases being 60 pivoted on the said pivot pins to pull the

cars along and to allow the cars to swing sidewise, the said pivot pins being adapted to be engaged by the said drum lugs to impart a traveling motion to the said cable, a gear wheel on each car body, and segmental 70 racks arranged concentrically on the ends of the guideway to rotate the car bodies.

10. A pleasure railway, comprising a platform having an endless guideway, cars each having a base and a car body mounted to turn 75 on the said base, the latter being mounted to travel on the said platform, propelling means in the form of an endless traveling cable arranged below the said platform, a driving drum around which passes the said 80 cable, means connecting the said drum with the cable to impart a traveling motion thereto, pivot pins extending upward from the cable through the said guideway, the said car bases being mounted to swing on the said 85 pivot pins, and guide pins intermediate the pivot pins and attached to the cable, the said guide pins engaging the said guideway.

11. A pleasure railway, comprising a platform having an endless slot, a guideway having a continuous segmental end portion on the under side of the platform and having an interrupted segmental portion at the other end, the guideway being formed of angle irons arranged on opposite sides of the said slot and following the same, the outermost angle iron being continuous and segmental at the ends of the guideway, and the inner angle iron terminating at its ends at one of the segmental end portions of the guideway, 90 a driven drum on the interrupted end portion of the guideway, cars mounted to travel on the said platform, an endless cable passing around the said drum, pivot pins attached to the cable and mounted to travel between 95 said angle irons of the said guideway, the said pivot pins extending through the said slot and connecting with the said cars, and lugs on the said drum engaging the said pivot pins to impart a traveling motion to 100 the said cable.

12. A pleasure railway, comprising a platform having an endless slot, a guideway having a continuous segmental end portion on the under side of the platform and having 115 an interrupted segmental portion on the other end, the guideway being formed of angle irons arranged on opposite sides of the said slot and following the same, the outermost angle iron being continuous and seg- 120 mental at the ends of the guideway and the inner angle iron terminating at its ends at one of the segmental end portions of the guideway, a driven drum at the interrupted end portion of the guideway, cars mounted 125 to travel on the said platform, an endless cable passing around the said drum, pivot pins attached to the cable and mounted to travel between said angle irons of the said guideway, the said pivot pins extending 130

through the said slot and connecting with the said cars, lugs on the said drum engaging the said pivot pins to impart a traveling motion to the said cable, and guide pins 5 mounted to travel between the said beams and attached to the said cable intermediate the pivot pins.

13. A pleasure railway, comprising a platform, a car having a car base and a car body 10 mounted to turn on the said base, the latter

having means engaging the said platform to support the car on the platform and to allow it to travel thereon, means propelling the said car base along an endless path extending over the said platform, and means 15 periodically turning the car body on the car base during the latter's travel along the path.

MARCUS JOHNSON.
